PAINT BRUSH PROTECTOR

Gustaf Sigfrid Hanson, Montclair, N. J.

Application July 3, 1933, Serial No. 678,809

4 Claims. (206—15.1)

To obtain best results in the use of paint brushes, it is essential that the bristle end of the brush should taper down to a "chisel point" and should be flexible.

5 However, in practice, after the paint brush has been used for some time, the bristles become distorted and divided into groups which adhere together, due to the common practice of positioning the brushes in paint pots and the like when not in use. Frequently brushes are placed in the same paint pot after having been used with paints of different colors with the result that the paints of the brushes mix and the brushes must be tediously cleaned before they can again be used.

10 While the cost of the average paint brush is not very great, the item of replacement of paint brushes is a very considerable one where large numbers of brushes are used, particularly brushes 20 of the type used for specialized work.

This invention relates to paint brush protectors designed to prolong the useful life of paint brushes by preventing the distortion of the bristle end of the brush, and has as its object to provide 25 a device of this character which lends itself readily to economical manufacture from suitable metal by simple tools and dies, is compact and complete in itself, efficient and positive in operation, and may be readily applied to and removed 30 from paint brushes.

It is a further object of my invention to provide a paint brush protector adapted to be stamped out of ordinary sheet metal in large 35 quantities at a negligible cost so that the same may be distributed gratuitously for advertising purposes by manufacturers and others or may be purchased, at low cost, by paint brush users.

It is another object of my invention to provide a paint brush protector which is of such simple construction that no skill or particular attention is required to use it, thereby assuring its use 40 by even the most careless individuals and by those who, due to their mechanical inexperience, would shun a complicated structure.

45 It is a further object of my invention to provide a paint brush protector made from a single blank of suitable metal adapted to be readily folded into its completed position and to be easily opened from time to time in order to clean the same.

A further object of my invention is to provide a paint brush protector designed to enable the free circulation of liquids through the protector and around the paint brush positioned therein.

55 A further object of my invention is to provide

a paint brush protector of fool-proof construction consisting of a minimum number of parts, which will not get out of order in use.

These and other advantageous objects which will later appear, are accomplished by the simple and practical construction and arrangement of parts hereinafter described and exhibited in the accompanying drawing, forming part hereof, and in which:

Fig. 1 represents a perspective view of the paint 10 brush protector embodying my invention, shown positioned in a paint pot;

Fig. 2 represents a perspective view of the paint brush protector, showing, in dotted lines, the manner in which the same may be opened for 15 cleansing purposes;

Fig. 3 represents a top plan view of the blank from which the device is made, the blank being foldable along the dotted lines to make the complete device, and

Fig. 4 represents a transverse sectional view 20 taken on lines 4—4 of Fig. 2.

As shown in the drawing, my device is preferably made from a flat blank of suitable sheet metal, preferably spring metal, stamped or cut to form a handle 1 integral with the rear wall 2, the latter being preferably integrally connected with the front wall 3 at the folding line 4. The rear wall 2 is marginally bent along the lines 5 to provide inwardly extending flanges 6. The front wall 3 is provided with extended portions 7 foldable along the lines 8 to provide curved holding elements or lugs 9 (see Fig. 2) adapted to snap over the flanges 6. The lower ends of the inwardly extending flanges 6 are brought closer to the rear wall 2 of the device (see Fig. 4) than the upper ends thereof (see Figs. 1 and 2) thereby providing a V-shaped pocket 10 for the reception of the bristle end of the paint brush 11.

Inasmuch as the device, as previously stated, is 40 preferably made from spring metal, the front wall 3 with its attached holding lugs 9 can be readily disengaged from the inwardly extending flanges 6 with which said lugs have holding engagement, and may be brought forward, into the 45 position shown in dotted lines in Fig. 2, to facilitate the cleaning of the device.

The lower ends of the flanges 6 are inwardly directed to space them from the front wall 3 (see Fig. 4) so that, when the device is inserted 50 into a paint pot 12, as shown in Fig. 1, the paint or brush cleaning liquid 13 may freely circulate through the device and around the bristle end of the brush, and will not coagulate, as would be the case where no free circulation is provided. The 55

protector may be positioned in a paint pot or the like while the brush is not in use or may be positioned in a softening or cleansing liquid which will circulate therethrough to further effectuate 5 the preservation of the paint brush.

The front wall 3 may be brought closer or farther away from the rear wall 2 by merely directing the flanges 6 at the point at which the lugs 9 of the front wall engage the same, outwardly or 10 inwardly, as desired, to enable the device to accommodate paint brushes of various dimensions and sizes. The front wall 3 may also be bent to 15 accommodate oval-shaped paint brushes, and the device may be made in various sizes and dimensions for use in connection with paint brushes of various sizes.

If it is desired, the handle may be offset rearwardly from the rear wall 3 and may be provided with a depressed portion 14 designed to engage 20 with the edge of the receptacle 12 in which the device is positioned, to prevent the device from slipping from its vertical position therein.

The device described above may be readily manufactured by the use of suitable tools and dies, 25 at such low cost that the same may be distributed free for advertising purposes or as a premium, and, for this purpose, the front wall 3 is admirably adapted to bear advertising matter as shown in Fig. 1.

The foregoing disclosure is to be regarded as 30 descriptive and illustrative only, and not as restrictive or limitative of the invention, of which obviously an embodiment may be constructed including many modifications, without departing 35 from the general scope herein indicated and denoted in the appended claims.

Having thus described my invention, what I claim as new and desire to secure by Letters Patent, is:

40 1. A paint brush protector, comprising a front wall and a rear wall provided with a handle ex-

tending upwardly therefrom, said handle being provided with a depressed portion designed to have engagement with the edge of the receptacle in which the device is positioned, to prevent the device from slipping from its vertical position 5 therein.

2. A paint brush protector made from a single blank of metal, comprising a rear wall provided with inwardly extending flanges and a front wall provided, at its upper end, with lugs adapted to have holding engagement with said flanges, to removably secure said walls together, the upper ends of said flanges being spaced farther from the rear wall than the lower ends thereof, to provide a unitary V-shaped paint brush receiving 10 15 pocket.

3. A paint brush protector made from a single blank of metal comprising a rear wall provided with inwardly extending marginal flanges and a front wall integrally connected with said rear 20 wall and provided with lugs adapted to snap over and have holding engagement with said flanges to removably secure said walls together, thereby providing a V-shaped paint brush receiving pocket, said front wall being spaced from 25 the marginal flanges to enable the free circulation of liquid through the protector and around the paint brush positioned therein.

4. A paint brush protector made from a single blank of metal comprising a rear wall provided with outwardly curved and inwardly extending flanges, and a front wall integrally connected with said rear wall and provided, at its upper and, with curved lugs adapted to snap over and have holding engagement with the outwardly 30 35 curved portion of said flanges, to removably secure said walls together, said flanges, along a portion of their length, being spaced from the front wall to enable liquids to freely circulate through the protector.

GUSTAF SIGFRID HANSON. 40
